(57) **ABSTRACT**

A waiting tray is provided in a sheet-conveying path and holds sheets if the sheets need to be post-processed. A processing tray receives sheets conveyed from the waiting tray. It may receive sheets conveyed through the sheet-conveying path and coming not via the waiting tray, before the sheets are post-processed. A conveying mechanism is provided, which causes the sheets to fall, due to gravity, from the waiting tray onto a processing tray. A sheet-aligning mechanism aligns the sheets on the processing tray, at their transverse edges and longitudinal edges. On the processing tray, the sheets are post-processed, forming a bundle. The conveying mechanism conveys the bundle of sheets to a storage tray. Input rollers are spaced by a vertical distance from sheet-feeding rollers which are positioned at upstream of the waiting tray.

SHEET POST-PROCESS APPARATUS

CROSS-REFERENCE TO RELATED APPLICATIONS

This application is based upon and claims the benefit of priority from prior Japanese Patent Application No. 2004-282212, filed Sep. 28, 2004, the entire contents of which are incorporated herein by reference.

BACKGROUND OF THE INVENTION

1. Field of the Invention

The present invention relates to a sheet post-process apparatus, such as a finisher, which is designed for installation at the outlet side of a multi-function peripheral (MFP).

2. Description of the Related Art

An apparatus called "finisher" is known, which receives printed sheets supplied from an MFP and staples them together. In the finisher, the sheets supplied from the MFP are sequentially conveyed to a tray and stapled by a stapler, forming a bundle of sheets. The bundle of sheets is ejected from the apparatus onto a storage tray.

Jpn. Pat. Appln. KOKAI Publication No. 6-99070 discloses a finisher. This finisher performs a post-process on sheets. In the post-process, a stapler staples sheets. To process the sheets at the same rate as the MFP processes them, it is necessary to reduce the speed at which sheets are conveyed in the finisher. The finisher therefore has a long sheet-conveying path.

Having a long sheet-conveying path, the finisher cannot be as small as desired.

BRIEF SUMMARY OF THE INVENTION

An object of the present invention is to provide a sheet post-process apparatus in which sheets can be conveyed onto the waiting tray smoothly at high efficiency.

A sheet post-process apparatus according to this invention comprises: a plurality of rollers which receive sheets from an MFP and convey the sheets forward; a waiting tray which is provided in a conveying path and holds the sheets conveyed from the rollers when the sheets need to be post-processed; a processing tray which holds the sheets conveyed from the waiting tray and the sheets conveyed via the conveying path without being conveyed to the waiting tray, before the sheets are post-processed; a conveying mechanism which causes the sheets to fall, due to gravity, from the waiting tray onto the processing tray; a sheet-aligning mechanism which aligns the sheets with one another on the processing tray, at transverse edge and longitudinal edge, thereby forming a bundle of sheets; a post-process mechanism which performs a post-process on the bundle of sheets on the processing tray; sheet-conveying means for conveying the bundle of sheets from the processing tray; and a storage tray which holds the bundle of sheets conveyed from the processing tray. The rollers include input rollers and sheet-feeding rollers. The input rollers are spaced by a vertical distance from the sheet-feeding rollers which are positioned at upstream of the waiting tray.

Preferably, the sheet-conveying path extending from the input rollers to the sheet-feeding rollers may be curved.

Preferably, the input rollers may be positioned above or below the sheet-feeding rollers.

In the apparatus, the waiting tray holds sheets to be post-processed. The conveying mechanism causes these sheets to fall, due to gravity, onto the processing tray. Hence,

it suffices to provide a sheet-waiting section that is just as long as the waiting tray. This renders the sheet post-process apparatus small.

Since the input rollers are spaced by a vertical distance from the sheet-feeding rollers which are positioned at upstream of the waiting tray, the sheet-conveying path extending from the input rollers to the sheet-feeding rollers can be curved and, thus, be longer than otherwise. Each sheet is curved as it is conveyed from the input rollers to the sheet-feeding rollers, becoming stiff and firm and making no irregular motions. It will not deviate from the conveying path.

BRIEF DESCRIPTION OF THE SEVERAL VIEWS OF THE DRAWING

FIG. 1 is a perspective view of a post-process apparatus according to this invention;

FIG. 2 is a top view of the post-process apparatus according to the invention;

FIG. 3 is a perspective view illustrating how the waiting tray of the post-process apparatus performs its function;

FIG. 4 is a perspective view depicting the sheet-bundle conveying mechanism provided in the post-process apparatus, and explaining how sheets are aligned at longitudinal edges in the post-process apparatus;

FIG. 5 is a perspective view showing the mechanism for aligning sheets at their transverse edges;

FIG. 6 is a perspective view illustrating how the stapler provided in the post-process apparatus performs its function;

FIG. 7 is a sectional view of the post-process apparatus, showing how the first sheet moves from the input rollers to the sheet-feeding roller;

FIG. 8 is a sectional view of the apparatus, explaining how the first sheet moves from the sheet-feeding rollers to the waiting tray;

FIG. 9 is a sectional view of the apparatus, explaining how the second sheet moves from the sheet-feeding rollers to the waiting tray;

FIG. 10 is a sectional view of the post-process apparatus, showing how the waiting-tray rollers operate;

FIG. 11 is another sectional view of the apparatus, illustrating how the waiting-tray rollers operate;

FIG. 12 is a sectional view of the apparatus, explaining how an active drop is carried out;

FIG. 13 is a sectional view of the apparatus, explaining how the third sheet is conveyed;

FIG. 14 is a sectional view of the apparatus, illustrating how the stapler operates;

FIG. 15 is a sectional view of the apparatus, explaining how a bundle of sheets moves between the processing tray and the storage tray;

FIG. 16 is a sectional view of the apparatus, illustrating how sheets move from the waiting tray to the storage tray;

FIG. 17 is a sectional view of the apparatus, explaining how the position of the storage tray is changed; and

FIG. 18 is a sectional view, representing the positional relation between the input rollers and the sheet-feeding rollers.

DETAILED DESCRIPTION OF THE INVENTION

An embodiment of this invention will be described, with reference to the accompanying drawings.

FIG. 1 is a perspective view of a sheet post-process apparatus according to this invention. FIG. 2 is a top view

of the post-process apparatus. As FIG. 1 shows, the post-process apparatus comprises a waiting tray 10, a processing tray 12, a stapler 14, a first storage tray 16, and a second storage tray 18.

The sheet post-process apparatus further comprises a pair of input rollers 22, a pair of sheet-feeding rollers 24, and an input-roller motor 26. The input rollers 22 receive a sheet 20 supplied from an MFP and convey the sheet 20 to the sheet-feeding rollers 24. The sheet-feeding rollers 24 convey the sheet 20 to the waiting tray 10. The input-roller motor 26 drives the input rollers 22.

One of the input rollers 22 is an upper input roller 22a, and the other input roller 22 is a lower input roller 22b. Likewise, one of the sheet-feeding rollers 24 is an upper sheet-feeding roller, and the other sheet-feeding roller 24 is a lower sheet-feeding roller.

The waiting tray 10 comprises two tray parts 10a and 10b. The tray parts 10a and 10b can move from left to right, and vice versa. When the tray parts 10a and 10b take a closed position, the waiting tray 10 can receive sheets. Waiting-tray rollers 28, a waiting-roller drive 30 and a waiting-roller motor 32 are provided. The waiting-tray rollers 28 align sheets on the tray parts 10a and 10b while both tray parts remain in the closed position. The waiting-tray rollers 28 can move up and down when they are driven and controlled by the waiting-roller drive 30. The waiting-roller motor 32 rotates the waiting-tray rollers 28.

When the number of sheets 20 stacked on the waiting tray 10 reaches a prescribed value, a waiting-tray motor 34 drives the waiting-tray parts 10a and 10b to an opened position as is illustrated in FIG. 3. The sheets 20 fall onto the processing tray 12, due to gravity. This event is known as "active drop."

The sheet post-process apparatus has a paper guide 36, which guides sheets from the MFP to the waiting tray 10 and thence to the processing tray 12. The paper guide 36 has a paper-pass ceiling.

In the processing tray 12, the sheets are aligned at the longitudinal edges and the transverse edges. The sheets are aligned at their longitudinal edges by a longitudinal-alignment mechanism 38 as is illustrated in FIG. 4. More precisely, an upper longitudinal-alignment motor 40 drives the upper longitudinal-alignment rollers 38a of the mechanism 38, and a lower longitudinal-alignment motor 42 drives the lower longitudinal-alignment rollers 38b of the mechanism 38. Driven by the motors 40 and 42, the rollers 38a and 38b move the sheets until one longitudinal edge of every sheet abuts on a stopper 45. Paddles 44 are provided to facilitate the longitudinal alignment. A paddle motor 46 drives the paddles 44.

The sheets are aligned at their transverse edges, too, as is illustrated in FIG. 5. More specifically, the transverse alignment is performed by a transverse-alignment mechanism 47 and a transverse-alignment motor 48.

When the number of sheets thus aligned in the processing tray 12 reaches the prescribed value, the stapler 14 starts operating. The stapler 14 is positioned as depicted in FIG. 6 and controlled by a stapler-driving unit 49.

Controlled by the unit 49, the stapler 14 staples the sheets together, forming a bundle of sheets. As shown in FIG. 4, a transport mechanism 50 transports the bundle of sheets to the first storage tray 16. Either the first storage tray 16 or the second storage tray 18 is selected when a storage-tray driving unit 52 (FIG. 2) moves the tray 16 or 18 to a predetermined upper position.

How the post-process apparatus according to this invention operates will be explained with reference to FIGS. 7 to 17.

As FIG. 7 shows, a sheet 20 conveyed from the MFP is moved from the input rollers 22 to the sheet-feeding rollers 24, in the direction of the arrow.

As is illustrated in FIG. 8, the sheet 20, or the first sheet, 5 is placed on the waiting tray 10. Then, the waiting-tray rollers 28 move down, in the direction of the arrow, aligning the trailing edge of the first sheet 20 at the rear (i.e., upstream) end 60 of the waiting tray 10.

As FIG. 9 depicts, the waiting-tray rollers 28 moves up to 10 receive the second sheet 20a.

As FIG. 10 shows, the second sheet 20 is conveyed to the waiting tray 10. The waiting-tray rollers 28 move down, aligning the trailing edge of the second sheet 20a at the rear 15 end 60 of the waiting tray 10. Thus, a bundle 20b of two sheets 20 and 20a is formed in the waiting tray 10.

As FIG. 11 shows, the waiting-tray rollers 28 move upwards. Then, the waiting-tray parts 10a and 10b move to the opened position as is illustrated in FIG. 3. The active drop 20 is therefore performed as shown in FIG. 12. The bundle 20b is conveyed to the processing tray 12.

Thereafter, the third sheet 20c and some following sheets are conveyed from the sheet-feeding rollers 24 to the processing tray 12, not through the waiting tray 10. These sheets are laid, one after another, upon the bundle 20b of two sheets. A bundle 21, which consists of the prescribed number of sheets, is formed on the processing tray 12. As the sheets including the third sheet 20 are sequentially laid on the bundle 20b, the longitudinal-alignment rollers 38 and the transverse-alignment mechanism 47 align the sheets at their 30 longitudinal edges and transverse edges.

The waiting tray 10 must be positioned so that its rear end 60 may lie downstream of the rear end (upstream-side) of the processing tray 12 when the sheets are laid on the bundle 20b. As shown in FIG. 13, the rear end 60 of the waiting tray 35 10 is therefore spaced from the rear end 62 of the processing tray 12, by distance L1, in the transverse direction. This enables the bundle 20b to fall smoothly from the waiting tray 10 onto the processing tray 12. This also makes it easy for both alignment mechanisms 38 and 47 to align sheets. Thus, 40 jamming of sheets can be prevented.

It is desired that the waiting tray 10 and the processing tray 12 be inclined, having their upstream ends at a lower position than their downstream ends. In other words, they should be so positioned that their rear ends 60 and 62 lie at the lowest position. If the trays 10 and 12 are so inclined, the sheets 20 are aligned, due to gravity, at the rear end 60 of the waiting tray 10, and the bundle 20b can be aligned, due to gravity, at the rear end 62 of the processing tray 12.

As seen from FIGS. 10 to 13, the sheet post-process apparatus has the following three characterizing features:

- (1) The waiting tray 10 extends longer in the sheet-conveying direction than the length of sheets 20.
- (2) The processing tray 12 extends shorter in the sheet-conveying direction than the length of sheets 20.
- (3) Because of the feature (2), any sheet 20 that has fallen from the waiting tray 10 onto the processing tray 12 is supported not only by the processing tray 12, but also by the first storage tray 16.

These features (1), (2) and (3) reduce the size of the sheet post-process apparatus (i.e., finisher) in the sheet-conveying direction.

As FIG. 14 shows, the stapler 14 staples the bundle 21 of sheets. Then, the transport mechanism 50 transports the bundle 21 to the storage tray 16 as illustrated in FIG. 15. Thus, the post-process ends.

If the sheets need not undergo the post-process, they are not conveyed to the processing tray 12. They are ejected

5

from the waiting tray 10 onto the first storage tray 16 as shown in FIGS. 16 and 17. As FIG. 16 shows, the sheets supplied from the MFP are sequentially conveyed to the first storage tray 16 via the input rollers 22, sheet-feeding rollers 24 and waiting tray 10. The waiting-tray rollers 28 move down, serving to convey sheets 20. As depicted in FIG. 17, the storage-tray driving unit 52 lifts the first storage tray 16 a little and receives the sheets coming from the waiting tray 10.

The positional relation between the input rollers 22 and the sheet-feeding rollers 24 will be explained, with reference to FIG. 18. As FIG. 18 depicts, these rollers 22 and 24 are so positioned that the input rollers 22 lie above, and spaced by vertical distance L2 from, the sheet-feeding rollers 24. Conversely, the input rollers 22 may be positioned below the sheet-feeding rollers 24. In which case, too, the input rollers 22 are spaced from the sheet-feeding rollers 24 by vertical distance L2. Thanks to distance L2, a curved path is provided, which extends from the input rollers 22 to the sheet-feeding rollers 24 as shown in FIG. 18. Curved, the path is relatively long. This makes it easy to control the speed of rotation of the sheet-feeding rollers 24. Since each sheet is curved as it is conveyed from the rollers 22 to the rollers 24, it is stiff and firm, making no irregular motions, and will not deviate from the conveying path.

One embodiment of the invention has been described. The invention is not limited to the embodiment, nevertheless. The components described above may be replaced with other components that are identical in function.

What is claimed is:

1. A sheet post-process apparatus, comprising:
a plurality of rollers which receive sheets from an MFP and convey the sheets forward;
a waiting tray which is provided in a conveying path and holds some of the sheets conveyed from the rollers when a bundle of sheets needs to be post-processed;
a processing tray which holds the sheets conveyed from the waiting tray and other sheets forming the bundle of sheets, before the bundle of sheets is post-processed;
the plurality of rollers including input rollers and sheet-feeding rollers, and the input rollers being positioned above the sheet-feeding rollers which are positioned upstream of the waiting tray and convey the sheets to the waiting tray or the processing tray;

45 a post-process mechanism which performs a post-process on the bundle of sheets on the processing tray; and
a storage tray which holds the bundle of sheets conveyed from the processing tray.

2. The sheet post-process apparatus according to claim 1, wherein a sheet-conveying path extending from the input 50 rollers to the sheet-feeding rollers is curved.

3. A sheet post-process apparatus, comprising:
conveying means for receiving sheets from an MFP and conveying the sheets forward;

55 a waiting tray which is provided in a conveying path and holds some of the sheets conveyed from the conveying means when a bundle of sheets needs to be post-processed;

a processing tray which holds the sheets conveyed from the waiting tray and other sheets forming the bundle of 60 sheets before the bundle of sheets is post-processed;

6

the conveying means including input rollers and sheet-feeding rollers, and the input rollers being positioned above the sheet-feeding rollers which are positioned upstream of the waiting tray and convey the sheets to the waiting tray or the processing tray;

a post-process mechanism which performs a post-process on the bundle of sheets on the processing tray; and
a storage tray which holds the bundle of sheets conveyed from the processing tray.

4. The sheet post-process apparatus according to claim 3, wherein a sheet-conveying path extending from the input rollers to the sheet-feeding rollers is curved.

15 5. The sheet post-process apparatus according to claim 1, further comprising a sheet-conveying mechanism which conveys the post-processed bundle of sheets from the processing tray.

20 6. The sheet post-process apparatus according to claim 3, further comprising a sheet-conveying mechanism which conveys the post-processed bundle of sheets from the processing tray.

25 7. The sheet post-process apparatus according to claim 1, further comprising a sheet-aligning mechanism which aligns the bundle of sheets with one another on the processing tray at transverse and longitudinal edges.

30 8. The sheet post-process apparatus according to claim 3, further comprising a sheet-aligning mechanism which aligns the bundle of sheets with one another on the processing tray at transvers and longitudinal edges.

9. The sheet post-process apparatus according to claim 1, further comprising an alignment mechanism to align some of the sheets on the waiting tray.

35 10. The sheet post-process apparatus according to claim 3, further comprising an alignment mechanism to align some of the sheets on the waiting tray.

11. A method for post-processing sheets, comprising:
receiving sheets from a multi-function peripheral and conveying the sheets forward;

40 positioning input rollers above sheet-feeding rollers which are positioned upstream of a waiting tray and convey the sheets to the waiting tray or a processing tray;

providing the waiting tray in a conveying path for holding some of the sheets conveyed when a bundle of sheets needs to be post-processed;

holding sheets conveyed by the waiting tray on the processing tray and other sheets forming the bundle of sheets before the bundle of sheets is post-processed;
performing a post-process on the bundle of sheets on the processing tray; and

holding the bundle of sheets conveyed from the processing tray.

12. The method for post-processing sheets according to claim 11, further comprising a sheet-conveying path extending from the input rollers to the sheet-feeding rollers to be curved.
